UNITED STATES PATENT OFFICE.

SALI SIMON, OF NEW YORK, N. Y.

DESIGN FOR SHELF-PAPER.

Specification forming part of Design No. 6,768, dated July 8, 1873; application filed June 16, 1873.

C.

To all whom it may concern:

Be it known that I, SALI SIMON, of the city, county, and State of New York, have invented a Design for Shelf-Paper, used to ornament the edges of shelves, of which the following is a specification:

The nature of my design is fully represented in the accompanying drawing, to which reference is made.

The design consists of two birds, A and B, arranged tail toward each other, one standing with the wings spread, and the other flying.

They are delineated on the paper by perforations.

The scalloping on the edge of the paper is no part of my design.

What I claim as my invention is—

The design for shelf-paper, essentially as shown and described.

SALI SIMON.
